UNITED STATES PATENT OFFICE.

JOSEPH JOHN BALK, OF BUFFALO, NEW YORK, ASSIGNOR TO MARKEL LIGHTING FITMENTS, INC., OF BUFFALO, NEW YORK, A CORPORATION OF NEW YORK.

DESIGN FOR A WALL PLATE FOR ELECTRIC-LIGHT FIXTURES.

Application filed February 10, 1926. Serial No. 16,474. Term of patent 3½ years.

To all whom it may concern:

Be it known that I, JOSEPH JOHN BALK, a citizen of the United States, residing at Buffalo, in the county of Erie and State of New York, have invented a new, original, and ornamental Design for Wall Plates for Electric-Light Fixtures, of which the following is a specification, reference being had to the accompanying drawing, forming part thereof.

In said drawing:

Figure 1 is a front elevation of a wall plate for electric light fixtures showing my new design.

Figure 2 is a side elevation of the same.

I claim:

The ornamental design for a wall plate for electric light fixtures, as shown.

JOSEPH JOHN BALK.
